UNITED STATES PATENT OFFICE.

PATRICK F. HANLEY, OF HOMESTEAD, PENNSYLVANIA.

ROLLING-MILL.

SPECIFICATION forming part of Letters Patent No. 413,141, dated October 15, 1889.

Application filed August 19, 1889. Serial No. 321,261. (No model.)

To all whom it may concern:

Be it known that I, PATRICK F. HANLEY, a citizen of the United States, residing at Homestead, in the county of Allegheny and State 5 of Pennsylvania, have invented or discovered a certain new and useful Improvement in Rolling-Mills, of which improvement the following is a specification.

In Letters Patent No. 352,748, dated November 16, 1886, and in an application, Serial No. 296,571, filed January 17, 1889, I have described and claimed certain improvements in feed-tables for rolling-mills, consisting in the mechanism for shifting said tables laterally 15 and vertically in accordance with the requirements of the mill, such improvements being effected by means of one or more fluid-pressure cylinders located on the table-supporting carriage through suitable interposed 20 mechanism; and in said application I have also described and claimed the arrangement of two similarly-moving tables on opposite sides of a pair of rolls, the simultaneous movements of both tables being effected by a fluid-pressure cylinder located on the carriage of 25 one of the tables and operating through suitable interposed mechanism.

The object of the invention described herein is to provide for the simultaneous vertical 30 and lateral adjustment of feed-tables arranged on opposite sides of a pair or train of rolls by means of fluid-pressure cylinders located in suitable relation to each table, operating through a suitable system of shafts, and 35 controlled in their operation from a pulpit or platform attached to one of the table-supporting carriages.

In general terms, the invention consists in the construction and combination of mechanical devices or elements, all as more fully hereinafter described and claimed.

In the accompanying drawings, forming a part of this specification, Figure 1 is a plan view of a rolling-mill plant embodying my 45 invention, a part of one of the tables being broken away. Fig. 2 is a sectional elevation of one of the tables and its carriage, and Fig. 3 is a sectional elevation showing the arrangement of gearing when the cylinders are 50 located as represented in dotted lines in Fig. 1.

In the practice of my invention two pairs or lines of rails 1 and 1^a are arranged on each side of the rolls A parallel with the axes of said rolls, as shown in Fig. 1. On these rails 55 are mounted suitable trucks having frames 2 and 2^a secured thereto, said trucks and frames forming carriages for the tables 3 and 3^a. The tables 3 and 3^a consist, as set forth in Letters Patent No. 352,748, of side plates 60 having feed-rolls mounted therein, said rolls being driven by a suitable train of gearing secured to the ends of said rolls. As stated in said Letters Patent, the tables are pivoted near the outer ends to posts projecting up 65 from the carriages, so as to permit of the vertical adjustment of the ends of the tables adjacent to the rolls A. For effecting this vertical movement curved racks 4 4^a are secured to the tables near their inner ends, and 70 pinions 5 5^a on the shafts 6 6^a intermesh with said racks, as shown in Fig. 2. The pinions 5 5^a are so keyed to the shafts as to rotate therewith while free to move therealong as the carriages are shifted laterally, as will be 75 hereinafter described. It is preferred, in order to prevent any twisting of the tables, to employ two racks, one secured to each side plate of each table, and two pinions, which are held in alignment with the racks by the 80 sides of the carriages and by collars 7, interposed between the pinions and surrounding the shafts, which are mounted at the ends in bearings 8 8^a and 9 9^a, their middle portions being supported by the sides of the carriages. 85 On the shafts 6 6^a are secured beveled pinions 10 10^a, intermeshing with correspondingly-shaped pinions 11 11^a on the ends of the shaft 12, which is also mounted in the bearings 8 8^a. On the shaft 12 is keyed a 90 pinion 13, with which a rack 14 intermeshes, said rack being connected to the piston-rod 15 of the fluid-pressure cylinder 16.

The lateral movements of the carriages are effected by pinions 17 17^a on the shafts 18 95 18^a, mounted in suitable bearings longitudinally of the carriages, said pinions engaging racks 19 19^a, arranged between the lines of rails 1 1^a, as shown in Fig. 1. On the inner ends of the shafts 17 17^a are secured the 100 beveled pinions 20 20^a, adapted to intermesh with similar pinions 21 21^a, so keyed to the

shafts 22 22^a as to move freely along the shafts while rotating therewith. The pinions 21 21^a are held in proper engagement with the pinions 20 20^a during the movement of 5 the carriages by means of sleeves 23 23^a, surrounding the shafts 22 22^a and interposed between the pinions and the sides of the carriages, as shown in dotted lines in Fig. 1. The shafts 22 22^a are mounted at their ends in 10 bearings 24 24^a and 25 25^a, and on said shafts are keyed the beveled pinions 26 26^a, intermeshing with correspondingly-shaped pinions 27 27^a on the shaft 28. This shaft is mounted at its ends in the bearings 24 24^a, 15 and has keyed thereto a pinion 29, adapted to engage the rack 30, connected to the piston-rod 31 of the fluid-pressure cylinder 32.

On one of the carriages, and preferably near its outer end, is secured a platform or 20 pulpit 33, on which the operator stands while shifting the levers 34 and 35, controlling the valve mechanisms 36 and 37 of the cylinders 16 and 32 through the medium of the rods 38 and 39, as shown in Fig. 1. Any other arrangement of the valves and their operating 25 mechanisms whereby the valves may be controlled from the pulpit 33 may be employed.

As shown in dotted lines in Fig. 1, the driving-shafts 12 and 28 and the beveled pinions whereby said shafts transmit motion 30 may be dispensed with, the fluid-pressure cylinders 16 and 32 being arranged at right angles to the shafts 6 6^a and 22 22^a, on which in such case pinions 13 13^a and 29 29^a will be 35 keyed and operated by racks 14 and 30.

While preferring to employ curved racks and pinions for raising and lowering the tables, as hereinbefore described, it will be evident to those skilled in the art that the bell- 40 crank levers described and shown in Letters Patent No. 352,748 and in the application hereinbefore referred to may be employed.

I claim herein as my invention—

1. In a rolling-plant, the combination of a 45 laterally-moving carriage, a table provided with feed-rolls pivoted thereto, a shaft having a pinion keyed thereto, a fluid-pressure cylinder independent or outside of the carriage and adapted through interposed gearing to

rotate said shafts, and stationary racks with 50 which said pinion intermeshes, substantially as set forth.

2. In a rolling-mill plant, the combination of a carriage, a table provided with feed-rolls pivoted thereto, a curved rack attached to 55 said table, a shaft having a pinion keyed thereto engaging the rack, and a fluid-pressure cylinder located outside of the carriage and adapted through interposed gearing to rotate the shaft, substantially as set forth. 60

3. In a rolling-plant, the combination of rolls, two carriages arranged on opposite sides of the rolls, tables pivoted to said carriages, racks arranged parallel with the axes of said rolls, shafts mounted on the carriages 65 and provided with pinions engaging the racks, and a fluid-pressure cylinder independent of or outside of the carriages and adapted through interposed gearing to rotate said shafts, thereby effecting a simultaneous lateral movement of both carriages, substantially as set forth. 70

4. In a rolling-mill plant, the combination of rolls, two frames or carriages arranged on opposite sides of the rolls, tables pivoted to the 75 carriages, curved racks secured to the tables, shafts having pinions keyed thereto engaging said racks, and a fluid-pressure cylinder located outside of the carriages and adapted through interposed gearing to rotate said 80 shafts, thereby moving both tables simultaneously, substantially as set forth.

5. In a rolling-plant, the combination of rolls, two frames or carriages arranged on opposite sides of the rolls, tables pivoted to the 85 carriages, fluid-pressure cylinders adapted by interposed gearing to shift the carriages and tables, a platform secured to one of the carriages, and levers connected to the valve mechanism of the cylinders and located in 90 convenient proximity to the platform, substantially as set forth.

In testimony whereof I have hereunto set my hand.

PATRICK F. HANLEY.
